Patented Oct. 4, 1921.

UNITED STATES PATENT OFFICE.

DAVID W. JONES, OF CHICAGO, ILLINOIS.

STEERING-GEAR.

1,392,646.

Specification of Letters Patent. Patented Oct. 4, 1921.

Application filed November 29, 1918. Serial No. 264,580.

To all whom it may concern:

Be it known that I, DAVID W. JONES, a citizen of the United States, and resident of Chicago, in the county of Cook and State 5 of Illinois, have invented a certain new and useful Improvement in Steering-Gears, of which the following is a description, reference being had to the accompanying drawing, which forms a part of my specification.

- 10 My invention relates to steering gears for motor driven vehicles; having for its object the provision of a construction which will possess the requisite strength to adapt it for use on motor driven trucks and the like; at 15 the same time providing a construction which may be easily manipulated and be smooth in its operation, and at the same time possessing great wearing quality and yet be simple in construction.
- 20 The advantages above enumerated, as well as others inherent in the construction, will be readily comprehended from the following detailed description of the accompanying drawing wherein:—
- 25 Figure 1 is a longitudinal central sectional view taken through the steering gear, with portions of the handle shown broken away.

Fig. 2 is an elevation of the lower portion of the steering gear, illustrating the 30 outer casing or housing, the view being taken from a point at right angles to Fig. 1.

Fig. 3 is a cross sectional view taken on the line 3—3 of Fig. 1, looking in the direction of the arrows.

As my invention relates to the steering gear proper, namely to mechanism whereby rotation of the steering column or shaft will transmit movement to the steering 40 wheels by means of the usual steering rod or link, the specific construction and method of mounting the steering column and other motor control mechanisms will not be described.

45 In the particular exemplification of the invention as disclosed in the drawing, the steering shaft 5 is shown inclosed in a suitable column or outer shell 6 on which is shown suitably mounted the usual carbureter and spark control mechanism at 7; the 50 exemplification being of the type more generally employed on motor driven trucks.

The lower end of the shaft 5 is shown as 55 preferably provided with a suitable worm-thread, as at 8, which terminates a short distance from the lowermost end of the shaft,

as shown in Fig. 1, where the end is shown somewhat reduced and has rotatable bearing in the internal web or flange 9 of the outer casing or housing 10; the lower end 60 of the shaft 5 being provided with suitable bushing, as at 11, which is disposed in a suitable aperture formed in the flange or web 9 of the housing so as to provide a suitable bearing for the shaft. 65

The worm portion 8 of the shaft is surrounded by a nut shown preferably in the form of a split sleeve 12 internally threaded to mesh with the worm portion 8 so as to travel lengthwise thereof when the shaft 5 70 is rotated.

The elongated nut on sleeve 12 has one side thereof provided with a lobe or ear, as at 13, to which is pivotally connected an arm 14 by means of bolt or pin 15. The 75 lower end of the arm 14 is pivotally connected by means of pin 16 to a rocker-arm 17, the opposite end whereof is either keyed or integrally secured to the trunnion 18 which has suitable bearing in the housing 80 or casing 10.

The trunnion 18 extends into and through a laterally disposed hub portion 19 of the housing 10, see Fig. 2. The end of the trunnion or stub-shaft 18, which extends 85 through to the exterior of the housing, is there provided with a lever 20, to which the usual steering link or reach rod is intended to be secured, whereby movement is transmitted to the steering arms or mechanism which control the forward or steering 90 wheels of the motor driven vehicle.

The elongated nut or sleeve 12 is shown provided with lobes, as at 21, adapted to receive bolts, as at 22 in Fig. 3, whereby the 95 nut or sleeve may be firmly contracted or drawn into snug or operative relation with the worm or sleeve-engaging portion 8 of the shaft 5.

The outer housing or casing 10 is preferably bisected or made in two sections, as shown in the drawing, to facilitate the assembling of the mechanism; the two sections being shown provided with correlated lugs having registering openings for the 100 passage of suitable bolts, as at 23. The construction of the casing or housing, as shown, permits ready access to the mechanism within as is apparent; and this housing 10 may in turn be provided with suitable lugs as at 24, 24 whereby it may be 105 suitably bolted to the supporting frame or

bracket, as illustrated for example at 25 in Fig. 1. Of course, it will be understood that any suitable means of support for the steering gear may be employed suitable to 5 any particular situation.

In order to overcome any turning tendency on the part of the elongated nut or sleeve 12 and at the same time provide suitable slide-way therefor, I have shown each section of 10 the housing or casing 10 provided with an elongated rib, as at 26, which may be suitably machined or surfaced. The ribs 26 are placed so as to contact with and provide a smooth surface for the heads of the pivot 15 pin or bolt 15 during movement of the nut or sleeve lengthwise of the worm portion of the shaft 5.

It is evident from the construction shown and described that rotation in one direction 20 of shaft 5 will cause nut or sleeve 12 to move downwardly on the worm portion of the shaft, inducing link or arm 14 to oscillate rocker-arm 17 toward the lower end of housing 10 and therefore also rotate the trunnion or stub-shaft 18. Such rotation of 25 trunnion 18 will induce the lever 20 to oscillate toward the left in Fig. 1. On the other hand, rotation of shaft 5 in the opposite direction will cause the elongated sleeve 30 or nut 12 to ride upwardly on the threaded portion 8 of the shaft causing an upward pull to be exerted on rocker-arm 17 through the medium of link or arm 14, so that lever 20 will be swung in the opposite direction 35 from that previously mentioned.

As is clearly evident from the construction, its operation will be extremely easy and quickly responsive, while at the same time possessing great strength and positive- 40 ness in the transmission of the desired movement. Furthermore, the construction provides smoothness in operation, while at the same time possessing great wearing qualities.

45 I have shown and described what I believe to be the simplest and best adaptation of my invention, but modifications may be made in certain details without, however, departing from the spirit of the invention.

50 What I claim is:—

1. A steering gear, comprising a two-part housing, a web disposed transversely from

one wall of the housing at a point removed from the lower end and terminating at a point removed from the opposite wall of the 55 housing, a shaft rotatably mounted at its lower end in said web, each part of the housing being provided with an elongated rib arranged in opposing relation and disposed parallel with the shaft, a single member en- 60 circling said shaft and having operative relation therewith whereby rotation of the shaft will cause said member to travel lengthwise of the housing, said member being provided with a laterally disposed por- 65 tion adapted to slide between said ribs to prevent rotative movement of said member, a lever oscillatingly mounted in the lower part of said housing, a rocker arm disposed transversely within the housing beneath said 70 web and having operative relation with said lever, and an arm disposed lengthwise intermediate of the web and the opposing wall of the housing, said arm being connected to said member and one end of said rocker arm 75 whereby movement of the member will induce oscillation of said lever.

2. Steering gear, comprising a housing composed of two sections removably secured together, each section being provided with 80 a corresponding transversely disposed web, each section being also provided with opposingly disposed elongated ribs, a screw shaft disposed lengthwise within the housing, with the lower end thereof having bearing 85 in said corresponding webs, a split sleeve member internally threaded to mesh with the threads of said shaft, means whereby the split sleeve may be drawn into close contact with said shaft, a portion of said sleeve 90 member being disposed between the opposingly disposed ribs of the housing to prevent rotation of said sleeve member, a rocker arm disposed transversely beneath the lower end of said shaft with one end thereof rotatively 95 secured in the housing sections, and an arm having one end pivotally secured to said sleeve member while the other end is pivotally secured to the free end of said rocker arm.

DAVID W. JONES.
